L. B. JOSEPH

SHOE

Filed Nov. 12, 1925

UNITED STATES PATENT OFFICE.

LESLIE B. JOSEPH, OF CINCINNATI, OHIO, ASSIGNOR TO THE P. GOLDSMITH SONS COMPANY, OF CINCINNATI, OHIO, A CORPORATION OF OHIO.

SHOE.

Application filed November 12, 1925. Serial No. 68,690.

My invention relates to the general class of shoes and particularly to athletic shoes of the lasted type.

It is the object of my invention primarily 5 to provide a shoe with a very flexible shank portion which will permit the bending of the foot within the shoe in an unhampered way. For many types of athletic and surgical uses in order to provide a durable shoe such 10 a stiff piece of leather has to be used for the insole that the foot will not be free to bend within the shoe. It is primarily my object in that special construction hereinafter described to provide a shoe in which the 15 shank portion is readily flexible and in which the foot of a wearer will be almost as free to bend as the foot would be without the shoe on.

Referring to the drawing in which I have 20 illustrated a preferred embodiment illustrating my invention:

Figure 1 is a side elevation of an athletic shoe with a cut-away portion showing the inner structure.

25 Figure 2 is a perspective view of a preferred type of inner sole to which the upper is lasted.

Figure 3 is a perspective view of the outer sole.

30 Figure 4 is a perspective view of the heel.

Figure 5 is a perspective view of a partial assembly of my novel shoe showing the upper lasted to the inner sole prior to the securing on of the outer sole and heel.

35 Generally indicated at 1 is the inner sole which, as illustrated in Figure 2, is cut with slits 2 extending transversely from the outer side of the insole inwardly to the inside surface of the insole. The slits are disposed in 40 the insole in the portions which on a wearer's foot would lie at the back of the ball and at the front of the heel. Separate outer sole pieces 3 and heel pieces 4 are provided which are secured on after the lasting 45 of the upper onto the insole.

In manufacturing my novel shoe the insole is first tacked to the last. The surface which is tacked to the last is that shown uppermost in Figure 2. Then the upper indicated at 5 is formed over the last and lapped over the sole and heel portion of the insole but extended through the slits 2 so that at the sides of the shank portion the lapped edges of the upper will lie on the inside of the shoe. The shoe upper and

insole are then lasted at the sides of the shank and the shoe is removed from the last and stitched along the shank as indicated at 6 for applying the outer sole and heel. The outer sole is then secured as indicated at 7 60 to the insole with the stitches extending through the outer sole, the lapped portion of the upper and the insole. The heel portion is then applied in a similar way. It is then preferable to sew the back end of the outer sole and the front end of the heel with stitching extending across the shoe as indicated at 8. The shoe is then finished in the usual manner. Depending on the particular requirements of the shoe, it is optional 65 with the manufacturer whether both the sole and heel are made in accordance with the foregoing description or whether the sole only is made accordingly.

70 It will be apparent from the foregoing description that I have provided a shoe with an unusually flexible shank portion and although I have illustrated the application of my invention to a simple athletic shoe I do not wish to limit myself to this type of shoe. To the best of my knowledge and belief no one has previously made a shoe in which the insole is exposed on the outside and forms the shank of the shoe with the upper firmly secured to the insole on the inside at the shank portion and between the insole and the outer sole in the sole or the sole and heel portions.

75 Having thus described my invention, what I claim as new and desire to secure by Letters Patent, is:—

1. A shoe comprising an insole with the upper lasted to the insole on the outside of said insole at the outer edges thereof and on the inside of the insole along the edges of the shank, and transverse slits in said insole adjacent the shank, the upper extending through said slits from one surface of the insole to the other.

100 2. A flexible arch shoe comprising in combination, an inner sole and an upper lasted to the inner surface of the insole in the shank portion and an outer sole for the shoe with the forward portion of the upper secured to the insole between the insole and the outer sole.

105 3. A flexible arch shoe comprising in combination, an inner sole and an upper, with the upper lasted to the upper surface of the insole in the shank portion, an outer sole for 110

the shoe with the forward portion of the upper secured to the insole between the insole and the outer sole, a heel for the shoe and the remainder of the upper secured to the heel portion of the insole and lying between the insole and the heel.

4. A flexible arch shoe comprising in combination, an inner sole and an upper, with the upper lasted to the upper surface of the insole in the shank portion, an outer sole for the shoe with the forward portion of the

upper secured to the insole between the insole and the outer sole, a heel for the shoe and the remainder of the upper secured to the heel portion of the insole and lying between the insole and the heel, the insole being provided with transverse slots with the edge of the upper disposed in the slots whereby the upper lies on the inner side of the insole in the shank portion only. 15
